UNITED STATES PATENT OFFICE.

GEORGE W. WELLS, OF AMESBURY, MASSACHUSETTS.

DOORSTOP.

Application filed January 10, 1924. Serial No. 685,368.

This invention relates to that class of devices which are employed for yieldably limiting the opening movement of doors, the most common use of such devices being for doors of closed body automobiles.

Prior to my invention a common form of stop for this purpose, which has been generally employed, comprises a slotted plate which is set into the top edge of the door 10 and in the slot of which one pivot of a link is adapted to slide, the opposite end of the link being pivoted to the door casing and the plate having a coiled spring in one end portion of the slot, which is arranged to be 15 engaged by the pivot which slides therein, as the latter is drawn into said slot end portion, at the end of the opening movement of the door, so that a yieldable resistance is provided to the further opening of the door. 20 While this device performs its intended function in a sufficiently satisfactory manner, it is expensive to use on account of its cost and the cost of installing it, the work of grooving the upper edge of the door and fitting the slotted plate thereto being an important item of expense, and the fact that water is liable to accumulate in the groove 25 is an objectionable feature.

The objects of my invention are to provide 30 a simple and effective form of door stop of the character above referred to, which may be both manufactured and installed at small expense as compared with prior devices. Also to provide a form of door stop which 35 will act as a buffer for the closing of the door and will act to open the door slightly when it is unlocked.

I accomplish these objects in the manner hereinafter described and illustrated in the 40 accompanying drawing in which:

Fig. 1 is a plan view of the top portion of a door and casing provided with a preferred embodiment of my invention and showing the door in open position.

Fig. 2 is a cross section at line $\alpha-\alpha$ of Fig. 4 and with the door in closed position.

Fig. 3 is a view similar to Fig. 1 on a larger scale and showing the door nearly closed.

Fig. 4 is a side view of the parts in closed position.

Fig. 5 is a detail view of the joint between the links in locking position.

In the drawing, a door 1 is indicated as 55 hinged at 3 to the casing 2, the casing hav-

ing the usual recessed edge portion to receive the door.

According to my invention I provide a pair of links 4 and 5, which are formed of flat strips of resilient metal of suitable 60 length, width and thickness for the purpose to be explained. Each link has each end portion thereof twisted or bent into a plane at right angles to the main portion thereof, forming an ear 6 on one end of the link 4, 65 the extreme end portion of which is rounded and has a pivot pin 7 in the center thereof which is mounted in a plate 8. The corresponding end of the link 5 also has a similarly formed ear 9 in which a round pin 10 70 is rigidly mounted, said pin 10 having a head 11 of greater length and width, which is adapted, in one position thereof, to enter the slot 12 of a plate 13, the longer dimension of said head being greater than the width 75 of said slot. The opposite end portions 14 and 15 of the links 4 and 5 are also formed similarly to each other, and are superimposed and connected by a pivot 16, and the end portion 14 is extended perpendicularly 80 to form a lug or finger 18, which is arranged to engage the edge of the portion 15, and to lock the links against unfolding movement at a point at which they will be held at an obtuse angle to each other. 85

In practice the plate 13 is first attached by screws to the under side of the top portion of the casing in an approximately predetermined position, the wood directly beneath the slot 12 being slightly grooved to receive 90 the head 11 of the pin 10. The latter is then held in such a position that the longer dimension of the head 11 is coincident with the slot 12 and then it is inserted in the slot and turned so that the under side of the head 95 rests on the inner or upper side of the plate and holds it in position therein, as shown in Fig. 2. The plate 8 is then attached by screws to the upper edge of the door in such a position that, when the door is fully closed, 100 the pivot 7 will be beneath the pin 10 and the latter will be in the end portion of the slot 12, next the hinge 3. The angular position of the head 11 with relation to the link 5 is such that, in all positions of the door, 105 the head will be held in more or less transverse relation to the slot, so that the pin 10 will be retained therein. One of the purposes of the slot 12 is to permit a certain amount of lost motion between the pivot pin 110

and plate to compensate for slight inaccuracies in setting up. Also, if the offset type of hinge shown is used, so that the axis of the hinge is at one side of the line of the folded position of the links, a certain amount of lateral motion of the pivot 10 is necessary to permit opening and closing without binding, particularly if the links break towards the hinge in closing, as shown.

10 In practice the length of the links 4 and 5 is such that, when they are attached to the door and casing in approximately the position in which they are designed to be attached, the finger 18 will engage the edge of 15 the end portion 15 of the other link when the door is opened to the fullest extent to which it is desired to permit it to be opened, as shown in the full line position of Fig. 1, so that further relative swinging movement 20 of the links on the pivot 16 is prevented. In this position the links will be locked at an obtuse angle to each other against further movement towards a position in which the links are in alignment, so that, if further 25 pressure is applied to the door to open it, as the links are of resilient material, the pull thereon tending to draw them into a straight line, will cause them to be sprung or flexed into bow like form, towards the 30 straight line between the pivots 7 and 10 on the door and casing, as indicated in the dotted line position of Fig. 1. Opening movement of the door beyond the open position intended is only permitted against the 35 yielding resistance of the links, and as soon as the force acting to open the door is removed, the resiliency of the links will return the parts to the full line position of Fig. 1. With this arrangement, therefore, the greater 40 the extent to which the door is opened beyond a predetermined position, the greater will be the yielding resistance opposing such opening, so that extreme opening movement of the door will be effectively cushioned.

45 As the door is swung from closed to open position the pin 10 will first be moved towards the opposite end of the slot 12 and, when the links become locked against further opening movement, it will be drawn back against the end of the slot next the hinge.

50 In the formation of the pivotally connected end portions 14, 15, the twisted portions of the metal are similarly formed and arranged, so that, when the links are swung into folded position, the sides thereof will engage from edge to edge. The formation of the links is such that this engagement 55 ends at the point where the twisted portion begins and from this point the intermediate resilient portions thereof diverge at a small acute angle, as shown in the full line position of Fig. 3. When the links are in this 60 position the door will not be fully closed and in the final closing movement thereof,

the end portion 6 will be swung over the end portion 9 and one, or both of the intermediate portions of the links will be flexed and held under tension while the door is closed and latched, as indicated in the dotted line 70 position of Fig. 3.

Under these conditions, the links act as an anti-rattler for the door, by holding the latch firmly against its striker, and, when the door is unlatched, they will act to push 75 the door slightly ajar, overcoming, or assisting in overcoming the friction which tends to hold door closed when unlatched.

80 While the above described construction may be variously modified without substantial effect on the results secured and without departing from the spirit of my invention, yet the form shown is the most advantageous of any of which I am at present aware, especially as the links may be readily 85 stamped from the sheet metal and the entire device may be manufactured at a small expense.

I claim—

1. In combination with a door and the casing to which it is hinged, a yieldable stop 90 for limiting the opening movement of the door comprising a swinging arm pivotally connected to the door and casing arranged to permit the door to swing between open 95 and closed positions, said arm having an intermediate resilient portion arranged to bend in the plane in which it swings, and means to limit the swinging movement of the arm, as the door is swung into open position, at a point at which it is oblique to a right line between its points of connection with the door and casing, to cause said portion to be flexed towards said line upon further opening movement of the door. 100

2. In combination with a door and the casing to which it is hinged, a yieldable stop 105 for limiting the opening movement of the door, comprising a pair of links pivoted together at their adjacent ends, and respectively pivoted at their opposite ends to the door and casing, to permit the links to swing towards a position of relative alignment as the door is opened, each of said links having a resilient portion between its said pivots 110 adapted to yield in the plane in which the link swings, said links having oppositely disposed faces adjacent their pivotal connection arranged to be moved into engagement to lock the links against swinging movement 115 towards said position, to cause them to be flexed towards said position on further opening movement of the door.

3. In combination with a door and the casing to which it is hinged, a pair of links 120 pivoted together at adjacent ends and respectively pivoted to the door and casing at their opposite ends, said links each having a stop face arranged to be engaged one with the other at the end of the opening move- 125 130

ment of the door to limit the relative swinging movement of the links at a point at which said links are held in oblique relation to each other, one of said links being transversely resilient to permit the same to be flexed towards a position in which the links would be in alignment, on further opening of the door.

4. In combination with a horizontally swinging door and casing to which it is hinged, a pair of links composed of flat strips of resilient metal having vertically disposed, horizontally resilient intermediate portions, and twisted portions at the ends 10 of said intermediate portions to form horizontal end portions, said end portions being superimposed and pivotally connected, and the opposite end portions of the links being pivotally connected to the door and casing 15 respectively, said links each having a face adjacent the connecting pivot thereof arranged to engage each other at the end of the opening movement of the door, to lock the links in oblique relation against relative 20 swinging movement towards a position of alignment and to cause said links to be flexed towards said position of alignment on further opening movement of the door.

5. In combination with a horizontally swinging door and its casing, a pair of links pivotally connected at adjacent ends and respectively pivoted at opposite ends to the door and casing, said links having two pairs of cooperatively engaging faces adjacent 30 their connecting pivot, one pair being arranged to limit the opening movement of said links at a point at which they are at an

obtuse angle to each other, and the other pair being arranged to limit their closing movement at a point at which the links are 40 at an acute angle to each other, and one of said links having a horizontally resilient intermediate portion arranged to be flexed in one direction on opening movement of the door beyond the position in which the opening movement of the links is limited and to be flexed in the opposite direction during the latter portion of the closing movement of the door, whereby movement of the door at the end of both its opening and closing movements will be yieldingly resisted. 45

6. In combination with a horizontally swinging door and its casing, a pair of horizontally resilient links pivotally connected at adjacent ends and respectively pivoted to 55 the door and casing at opposite ends, said links having two pairs of faces adjacent their connecting pivot, one pair being arranged to be engaged at the end of the opening movement of the door to lock said links 60 at an obtuse angle to each other, against further opening movement and the other pair of faces being arranged to be engaged near the end of the closing movement of the door when said intermediate portions are 65 held at an acute angle to each other, whereby said resilient portions may be flexed in one direction on opening movement of the door beyond a predetermined point and in the opposite direction during the latter portion 70 of its closing movement.

In testimony whereof, I have signed my name to this specification.

GEORGE W. WELLS.
